UNITED STATES PATENT OFFICE.

HAYDEN A. KERN, OF DAYTON, OHIO.

COMPOSITION TO FACILITATE THE TAPPING OF ALUMINUM OR THE LIKE.

1,041,484.

Specification of Letters Patent.

Patented Oct. 15, 1912.

No Drawing.

Application filed January 31, 1912. Serial No. 674,485.

To all whom it may concern:

Be it known that I, HAYDEN A. KERN, a citizen of the United States, residing in Dayton, in the county of Montgomery and State of Ohio, have invented a new and useful Composition of Matter Intended Particularly as a Composition to Facilitate Tapping of Aluminum or the Like, of which the following is a full and comprehensive 10 position and specification, being such as will enable an ordinary machinist to prepare and practice the same with absolute exactitude.

In tapping aluminum castings, for instance, that is in forming threads around in an aperture therein, great difficulty is experienced by reason of the chips or cuttings adhering and sticking between the threads of the tap-screw, thereby locking the tap-screw and necessitating its removal and cleaning before further advance can be made; in attempting to force the tap forward after it has stuck frequently results in breaking the tap-screw; all of which causes an inordinate amount of trouble and consequent loss of time and waste of material.

To overcome these troubles and objections is the primal object of my invention, also providing a new article of manufacture which can be made and sold at a comparatively low price, and which will be highly efficient in practice, especially in working aluminum or kindred metals.

Other objects and advantages may be suggested by the specification or may be found by practice, and that which is new will be set forth in the appended claims.

In order that the preparation and the use of my invention may be fully understood and appreciated I will now take up a detailed description thereof, in which I will set forth the invention as completely and as comprehensively as I may.

The basic element of my composition is of a ceraceous nature, such as beeswax or its equivalent, forming the body element which is to be brought to a plastic condition by the admixture of a solvent, such as gasoline or its equivalent, and in some instances by the addition of a thinner, such as turpentine or its equivalent, the latter also being employed as an odor neutralizer.

For tapping aluminum I have found that the following named proportions will give

the most satisfactory results: Beeswax, one 55 pound; gasoline, five pounds; turpentine, one pound. However the proportions given may be variously changed and the turpentine may be entirely dispensed with. In fact the gasoline may be dispensed with 60 and the turpentine may be employed instead. Or both the gasoline and the turpentine may be dispensed with, providing however that another solvent be employed instead. The essential requisite being that the 65 wax must be reduced to a usable paste.

The turpentine not only acts as a thinner, but the odor thereof, combined with the odor of the other ingredients, and by reason of the chemical actions set up by the interaction 70 of the elements, tend to negative the odor of all, thereby preventing the solution from being offensive or deleterious to the user.

In practice a small amount of the paste may be placed or spread on the tap-screw, by 75 means of a paddle or otherwise, then as the tap-bolt enters the aperture to be threaded the chips will not adhere to the tap but they will slide forward as the tap cuts its way, thereby making the tap-bolt to be self-cleaning, and permitting the operator to complete the threads in each aperture without stopping the forward movement of the tap, or without removing the tap from the aperture, until the threads are completed therein, 85 thereby overcoming the crux of tapping aluminum or the like, and accomplishing the desideratum of this invention.

It is evident that my invention may be employed for other uses than those stated, 90 and that the ingredients and the proportions may be variously changed, without departing from the spirit of my invention or sacrificing any of the advantages thereof.

Having now fully shown and described 95 my invention, and the best means for its preparation and use to me known at this time, what I claim and desire to secure by Letters Patent of the United States, is—

1. A composition to facilitate the tapping 100 of aluminum or the like consisting of beeswax and a solvent formed into a pasty condition.
2. A composition to facilitate the tapping 105 of aluminum or the like and consisting of beeswax, a solvent, and an odor neutralizing agent.
3. A composition to facilitate the tapping

of aluminum or the like, consisting of bees-wax and gasoline formed into a paste.

4. A composition to facilitate the tapping of aluminum or the like, consisting of bees-wax, gasoline, and turpentine, or their equivalents formed into a paste.

In testimony whereof I have hereunto sub-

scribed my name to this specification in the presence of two subscribing witnesses.

HAYDEN A. KERN.
